UNITED STATES PATENT OFFICE

163,968

STRAPLESS BRASSIÈRE SLIP

Max M. Saffir, New York, N. Y.

Application May 5, 1951, Serial No. 15,072

Term of patent 7 years

(Cl. D3—26)

To all whom it may concern:

Be it known that I, Max M. Saffir, a citizen of the United States of America, residing in New York, county of New York, and State of New York, have invented a new, original, and ornamental Design for a Strapless Brassière Slip, of which the following is a specification, reference being had to the accompanying drawing, forming part thereof.

Fig. 1 is a front view of a strapless brassière slip, showing my new design.

Fig. 2 is a rear view thereof.

I claim:

The ornamental design for a strapless brassière slip, substantially as shown.

MAX M. SAFFIR.
